UNITED STATES PATENT OFFICE

WILLIAM H. DAY, OF EAST HAVEN, CONNECTICUT, ASSIGNOR, BY MESNE ASSIGNMENTS,
TO REMINGTON RAND INC., OF NEW YORK, N. Y., A CORPORATION OF DELAWARE

INDEX OR FILE

Application filed March 14, 1925. Serial No. 15,548.

This invention relates to indexes or files, and more particularly to that class of indexes wherein a series of record-bearing members are arranged upon a support in such a manner that a marginal edge of each will be exposed to view. In some instances, it is desirable that these members be retained upon the support for convenience in retaining the proper sequence of the series, but that the data thereon be removable for reference or for filing away in another class of index. One way of accomplishing such a result is to construct the members in such a manner that another card or the like may be detachably secured thereto.

More specifically this invention relates to a class of indexes of this type wherein the superposed card when upon the holding member will either have its margin exposed to view or not, as desired, and it will be securely retained upon its holder yet readily removable therefrom. It is also advantageous to have provision in connection with means to hold a card upon one side of the holder for holding another card upon the reverse side of the holder, without causing the possibility of interference between them when either is removed therefrom or secured thereto. It is also desirable that the superposed card be retained against displacement laterally as well as longitudinally with respect to the holder.

One object of this invention, therefore, is to provide an improved form of card holder to which inserts or additional record-bearing cards may be readily secured and readily detached therefrom.

Other objects of this invention are to provide an improved form of card holder for use in indexes of the above class, of such construction that differently sized additional cards may be detachably secured thereto; that a card of one size may be detachably secured on one side of the holder, while a card of another size is detachably secured upon the other side; and that either of the added cards may be secured to or detached from the card holder without disturbing the other.

Still another object of this invention is to

provide card engaging means upon such a card holder, of economical and efficient construction, which will not appreciably increase the combined thickness of a complete series of overlapping record-bearing members and which will retain the superposed card against lateral as well as longitudinal displacement while mounted thereon.

To these and other ends, the invention consists of the novel features and combination of parts to be hereinafter described and claimed.

In the accompanying drawings:

Fig. 1 is a plan or face view of a frame member having a plurality of card holders embodying the features of my invention mounted thereon;

Fig. 2 is a section on line 2—2 of Fig. 1;

Fig. 3 is an enlarged section on line 3—3 of Fig. 1, through one card holder only and with superposed cards thereon;

Fig. 3^A is an enlarged side view of the corner-engaging means at the free edge of a card holder, shown in Fig. 1;

Fig. 4 is a view of the rear face of one of the card holders shown in Fig. 1;

Fig. 5 is a detail view of the development of the holder card-retaining means, in a card holder like those shown in Fig. 1;

Fig. 6 is a plan view of a slightly modified form of card holder which embodies a feature of my invention;

Fig. 7 is a view of the front face of another card holder of slightly modified form, which embodies features of my invention, and

Fig. 8 is an enlarged section on line 8—8 of Fig. 7.

The index card holder selected for illustrating the features of this invention, is provided with support engaging means which are similar to the means provided for the type of index cards described and claimed in Patent No. 1,048,056, issued to Irving Fisher, December 24, 1912.

The supporting frame 10, in this instance, is provided with an index card retaining strip 11, having flanged side edges 12 and 13, which are engaged by the above-mentioned support-engaging means, consisting

of rearwardly directed ears 14 and 15, usually cut from the material of the record-bearing members 16 which, in this instance, are in the form of index card holders.

5 The card holder 16 is preferably divided into two portions, one of which may be termed the base portion 17, and the other the flap portion 18. These portions are hingedly connected together, either by a 10 weakened line or by other suitable means at 19, the ears 14 and 15 being struck out from the material forming the base portion.

15 The flap portion 18 of the card holder 16, shown in Figs. 1 to 5, inclusive, is provided upon one of its faces with card-retaining means comprising card-corner receiving members 20 and 21, which are formed at the corners of the free edge of the flap portion 18, and are arranged to receive, in this instance, the lower corners of a superposed card 37. Corner-receiving strips 22 and 23 are formed from the body of the flap portion adjacent the hinged edge thereof, and are arranged to receive the upper corners 20 of the card 37. The card edge engaging portions 22^a and 23^a of the receiving strips 22 and 23, respectively, retain the inserted card 37 against disengagement in a perpendicular direction from the corner-engaging means 20 and 21. The side edge engaging portions 22^b and 23^b retain the inserted card 37 against displacement laterally upon the card holder, insuring engagement of the lower corners of the card 37 in the members 20 and 21. Corner-receiving slits 24, 25, 26 and 27 are also provided in the body of the flap portion 18, and are arranged to engage the corners of another superposed card 28.

20 The ears 14 and 15, the strips 22 and 23, the slits 24, 25, 26 and 27, with the material for the corner-receiving members 20 and 21 are all formed when the card is blanked from sheet material, each of the strips 22 and 23 being formed between a pair of slits 29 and 30 cut into the material in a diagonal direction, preferably at 45 degrees from the perpendicular, whereby the portions 22^a and 23^a are each vertically disposed relatively to the portions 22^b and 23^b, respectively. 25 The slits 24 to 27, inclusive, also are preferably formed at 45 degrees from the perpendicular, being spaced apart the required distance to be capable of allowing the corners of the required size of card 28 to be inserted therethrough, and to retain them against longitudinal and lateral displacement thereon.

30 The material for the card corner receiving members 20 and 21 (see Fig. 5) comprises a portion 31, integral with the flap portion 18 at each of the side edges adjacent the free corners thereof, and a portion 32 depending from the portion 31 in a direction parallel with the respective side edges. The members 20 and 21 are formed by bending

35 this material inwardly along the line 33 so that the portion 31 lies upon the front surface of the flap portion, and then bending the material along the line 34 rearwardly and upwardly about the free marginal edge 70 35 of the flap portion so that the portion 32 lies upon the rear surface of the flap portion, as shown in Fig. 4. Suitable means is 75 provided for securing the portion 32 to the flap portion, which may consist of glue predisposed upon the portion 32, or as illustrated, by other securing means such as a staple 36.

80 By means of the above construction the card holder 16 is adapted to readily receive an index or reference bearing card of one size upon one face thereof, and another reference-bearing card of another size upon the other face or both cards upon the same face. Due to the arrangement of the card-retaining means for each card, neither will interfere with the attaching or detaching of the other from the holder when one is 85 upon one side and the other upon the other side thereof, and each will be retained in its proper position thereon against lateral as well as longitudinal displacement relatively to the holder. One of the cards, in 90 this instance card 37, will have a margin 38 exposed to view when the holder 16 is secured upon the carrying or supporting frame 10 in series with others. Preferably the card 37 is used to post reference matter thereon not particularly private, while the card, in this instance card 28, secured upon the rear face of the card holder may be used to post data thereon of a more private nature, preferably to the same subject matter as that upon the card 37. One card, therefore, because of its exposed margin will 95 act as an index member of the subject matter of both cards retained upon the holder. It is obvious also that the margin 39 of the card holder 16 may also be impressed with data and, therefore, will likewise act as an 100 index of the subject matter when the card 37 is removed therefrom.

105 Fig. 6 illustrates a card holder 40 having means to engage and support but one card, the means being of somewhat similar 110 construction to that provided upon the rear of the card holder 16, shown in Figs. 1 to 5, inclusive, and like it in that the margin of the superposed card is not exposed to view. The slots 41, in this instance, are formed by cutting out material from the body of the card flap, whereby the corners of the superposed card 42 are more easily slipped into engagement therewith. In this instance, the margin 43 of the card holder 40 is impressed with the necessary index data for proper filing thereof, in a series like that shown in Fig. 1 and described above.

115 Figs. 7 and 8 illustrate a card holder 45 120

having means to engage and support the card 44, the means in this instance being somewhat similar to the means provided upon the front face of the card holder 16, illustrated in Figs. 1 to 5, inclusive. In this instance, the corner-engaging means 46 at the free margin of the flap portion 47 of the holder is of a somewhat modified construction, as is also the base portion 48. This card holder, like the card holders above described, is blanked from one piece of material, is provided with a weakened line or other suitable hinged connection 19, between the flap and base portions 47 and 48, respectively, and has the support-engaging ears 49 and 50, and the card-retaining ears 51 and 52 formed from the material of the base 48 and flap 47, respectively. The material 53 which forms the card corner engaging means 46 in this instance, is integral at 54 with the flap at the edge of the free margin 55 thereof, and is bent up over the front surface of the flap, as shown at Fig. 7, where it is suitably secured thereto adjacent the edges of the same, staples 56 being shown as one way of securing the two together. In this form of card holder, the ears 51 and 52 cooperate with the corner-engaging means 46 and the securing means or staples 56 to retain the inserted card against lateral displacement.

The base portion 48 of the card holder 45 is illustrated as being of double thickness. This construction adds strength at this point and is formed by previously folding over the edge portion of the blank before striking out the ears 49 and 50. This construction is usually desirable when the card holders are made of relatively thin material, such as paper, and stiffens the base portion as well as transversely resisting distortion of the entire card holder. It is obvious that the holder 45 could be provided with card-retaining means upon the reverse side, said means being of the form shown upon the rear of card holder 16 or the card holder 40, in which case the advantages of the card holders 16 would be obtained. Likewise, the card holder 16 could be supplied without the means to hold the card 28. In some instances, the retaining strips 22 and 23 could be omitted from card holder 16 and the corner receiving members 20 and 21 relied upon to prevent lateral displacement of a narrower inserted card or strip.

In some instances it has been found advisable and convenient to form the strip 60 of transparent material, and to place it in the position shown in Fig. 1, even when the card 37 is also in place, thus providing a transparent covering for the exposed margin 38 of the card 37 or the margin 39 of the card holder 16. The same advantageous result would be obtained by the provision of a transparent card detachably held between

and by the corner-engaging members of the card holder 45 of Fig. 7.

The card corner engaging members, when used to hold a card such as the card 60 and without the additional upper edge retaining members 22 and 23 or the ears 51 and 52, preferably are formed to extend along and over the side edge portions of the inserted card an amount sufficient to insure proper holding engagement therewith, the binding effect of the engaging members at the bend 33 or at the securing means 56 being the sole retaining means for the inserted card against slippage therefrom.

While I have shown and described certain preferred embodiments of my invention, it will be understood that the same is not limited thereto in all of the details, but is capable of many modifications and variations which will fall within the spirit of the invention and within the scope of the appended claims.

What I claim is:

1. In an index or file, a holder member for record cards comprising a card having a base portion and a flap portion connected thereto, said base portion having an integral fold attached thereto so as to form a double thickness of material for said base portion, a frame member, integral ears struck from said base portion adapted to engage said frame member whereby a series of holder members may be supported with their edges in overlapping relation, and means adjacent the lower edge of said flap member detachably supporting a record card.

2. In an index or file, a frame member having a plurality of card holders detachably mounted thereon in such a manner that a free margin of each may be exposed to view, a card detachably superposed upon one surface of one of said holders and another card detachably superposed upon the other surface of said holder, one of said cards extending to the free edge of said holder to cover the free margin thereof, the other card being spaced from the free edge of said holder.

3. In an index or file, a holder member for record cards comprising a card having a base portion and a flap portion connected integrally thereto by hinge means, a frame member, ears struck from said base portion adapted to engage said frame member, whereby a series of holder members may be supported with their edges in overlapping relation, and integral pocket-forming ears formed adjacent a margin of each flap portion, said pocket being adapted to support a record card, said flap portion having slits formed therein adapted to receive the corners of said record card, said base member, ears, hinge means, pocket-forming ears

and slits being adapted to be formed at a single stroke of a punch.

4. In an index or file, a holder member for record cards comprising a card having a base portion and a flap portion connected thereto, a frame member, lugs on said base portion adapted to engage said frame member whereby a series of holder members may be supported with their edges in overlapping relation, integral ears formed on said flap portion adjacent the lower edge thereof, said ears being adapted to be folded over and secured to said portion so as to form a pocket for detachably supporting a record card; and parts on said flap portion above said pockets for engaging a portion of the upper edge of said record card.

5. In an index or file, a holder member for record cards comprising a card having a base portion and a flap portion connected thereto, a frame member, lugs on said base portion adapted to engage said frame member whereby a series of holder members may be supported with their edges in overlapping relation, integral ears formed on said flap portion adjacent the lower edge thereof, said ears being adapted to be folded over to form pockets for the reception of the corners of a record card, and staples extending through said ears and flap portions securing said folded ears to said flap portion and adapted to engage the edges of said record card to prevent the lateral displacement thereof, and to prevent said ears from being cut by the edges of said card.

6. In an index or file having a frame member for supporting a plurality of card holders in overlapped relation with a free marginal portion of each in visible indexed relation, a card holder comprising a base portion for detachable engagement with the frame member, a flap portion hingedly connected to said base portion, pocket-forming members mounted over the corners of said flap portion at the ends of the free marginal portion to receive the corners of record cards, and staples extending through and securing said pocket-forming members to the ends of said flap portion, said staples engaging the edges of said record card to prevent lateral displacement thereof.

7. In an index or file having a frame member for supporting a plurality of card holders in overlapped relation with a free marginal portion of each in visible indexed relation, a card holder comprising a sheet having means on one marginal portion for hingedly connecting it with the frame member, an integral extension on the opposite free marginal portion formed to provide a fold overlying said free marginal portion to form a card-receiving pocket, and a fastener at the end of said free marginal portion engaging the extension and said marginal portion for retaining said extension in

8. A card holder for an index or file, comprising a sheet having means on one marginal portion for hingedly connecting it with an index or file, an integral extension on said free marginal portion formed to provide a fold overlying said free marginal portion to form a card-receiving pocket, and a fastener at the end of said free marginal portion engaging the extension and said marginal portion for retaining said extension in pocket-forming relation and preventing lateral displacement of a record card in the pocket.

8. A card holder for an index or file, comprising a sheet having means on one marginal portion for hingedly connecting it with an index or file, an integral extension on said free marginal portion formed to provide a fold overlying said free marginal portion to form a card-receiving pocket, and a fastener at the end of said free marginal portion engaging the extension and said marginal portion for retaining said extension in pocket-forming relation and preventing lateral displacement of a record card in the pocket.

In witness whereof, I have hereunto set my hand this 12th day of March, 1925.
